UNITED STATES PATENT OFFICE.

HORACE T. THOMAS, OF LANSING, MICHIGAN.

COOLING APPARATUS FOR AUTOMOBILES.

1,241,681.

Specification of Letters Patent.

Patented Oct. 2, 1917.

Application filed March 17, 1916. Serial No. 84,915.

To all whom it may concern:

Be it known that I, HORACE T. THOMAS, a citizen of the United States, residing at Lansing, county of Ingham, State of Michigan, have invented a certain new and useful Improvement in Cooling Apparatus for Automobiles, and declare the following to be a full, clear and exact description of the same, such as will enable others skilled in the art to which it pertains to make and use the same, reference being had to the accompanying drawings, which form a part of this specification.

My invention relates to cooling apparatus for automobiles and an object of my improvements is to provide an improved water cooling system for automobile engines and to provide for the rapid heating of the engine when it is starting and to automatically guard against too much cooling of the water in the radiator when the engine is at rest.

I accomplish this object in the device illustrated in the accompanying drawings in which,

Figure 1 is a side view partly in section of an apparatus embodying my invention and so much of an automobile engine as is necessary to illustrate its connection therewith.

Fig. 2 is a front elevation of the radiator.

a is an automobile engine having the water jacket *a*². *3* is the radiator or cooler. *b* is a water conduit leading from the radiator *3* to the lower portion of the water jacket *a*².

There is a centrifugal pump *4* adapted to be operated by the engine and to force the water through said conduit. *b*² is a conduit leading from the water jacket *a*² to the upper portion of the radiator *3*.

*b*³ is an enlargement in the conduit *b*². *b*⁴ is a thermostat adapted to nearly close the passage through the conduit *b*² when the cooling water is at a low temperature and to open said passage when the temperature of the water rises.

6 is a diaphragm chamber located in a casing at the upper part of the radiator *3* and having a flexible diaphragm or inner wall *6*^a. *5* is a tube communicating with the interior of the chamber *6* and with the enlargement *b*³ in the pipe *b*². *7* is a lever pivoted at *8* at one end and at the other end bent into a hook *7*^a adapted to engage a bell-crank lever *9*. The diaphragm *6*^a is connected at its center to the lever *7* so as to

oscillate said lever about its pivot *8* to actuate the bell-crank lever *9*.

10 indicates shutters adapted to open and close an area in front of the cooling tubes of the radiator *3*. The shutters *10* are pivoted at *10*^a and are connected together by pivoted rods *11*.

The bell-crank lever *9* engages against a lug extending from one of the connecting rods *11*. *10*^b is a spring acting to force the shutters *10* to their closed position.

The operation of the above described device is as follows:

When the engine is starting up the conduit *b*² is nearly closed by the thermostat *b*⁴ and there is a small amount of water in the jacket *a*² and between the jacket and the thermostat. As the engine begins to function it heats the small quantity of water quickly by which time it has gathered some speed.

The heat opens the thermostat *b*⁴ and the pressure of the water is conveyed through the pipe *5* to the chamber *6* where it presses the diaphragm *6*^a outward and oscillates the lever *7* thus opening the shutters *10* as indicated in dotted lines in Fig. 1.

When the engine stops, the pressure in the diaphragm *6* is relieved and the spring *10*^b draws the shutters back to their closed position thus preventing the cooling of the radiator tubes to the extent and at the rate at which it would otherwise occur.

What I claim is:

1. A combination including an internal combustion engine having a cooling system consisting in a complete circuit returning upon itself in which cooling liquid is circulated, said cooling system including a radiator, an outflow conduit leading from said engine to said radiator, a thermostat located in said out-flow conduit and adapted to substantially stop the circulation of liquid therein when said liquid is cool and to open said conduit when the water adjacent to said thermostat rises in temperature, whereby the water in said engine is held at rest until its temperature has risen to the desired temperature and is then permitted to circulate to regulate the temperature of the engine.

2. A combination including an internal combustion engine having a cooling circuit provided with a radiator, an out-flow conduit leading from said engine to said radi-

- ator, a thermostat located on the out-flow side of the engine and adapted to approximately close the out-flow conduit when the water is cool and to leave said conduit open 5 when the water is heated, a circulating pump and a motor communicating with the circuit beyond the thermostat, adapted to open up the radiator to the admission of air when a predetermined pressure due to the inertia 10 of the water and a predetermined temperature has been developed.
3. A combination including an internal combustion engine having a cooling circuit provided with a radiator and circulating 15 pump, and a motor communicating with said circuit and adapted to be actuated by the pressure of the liquid therein due to the inertia of the water, said motor being adapted to open up the radiator to the admission 20 of air.
4. A combination including an internal combustion engine having a cooling circuit provided with a radiator and circulating pump, and a motor communicating with 25 said circuit and adapted to be actuated by the pressure of the liquid therein due to the inertia of the water, said motor being

adapted to open up the radiator to the admission of air, said motor being connected to said circulating system adjacent to a 30 variation in the area of the passageway through said system.

5. The combination of an internal combustion engine having a cooling circuit provided with a radiator and a motor adapted 35 to be operated by the pressure due to the inertia of the water in said system for opening up the radiator to the admission of air.

6. A combination including an internal 40 combustion engine having a cooling circuit provided with a radiator and a circulating pump, a thermostat located in the circuit between the engine and radiator on the out-flow side of the engine, and a motor 45 communicating with the circuit beyond the thermostat, adapted to open up the radiator to the admission of air when a predetermined pressure and temperature has been developed. 50

In testimony whereof, I sign this specification.

HORACE T. THOMAS.
